CLAIM

The ornamental design for a paired base unit and receiver for wireless thermometer, as shown and described.

DESCRIPTION

FIG. 1 shows a perspective view of the front side of the receiver.

FIG. 2 shows a perspective view of the back side of the receiver.

FIG. 3 shows a perspective view of the front side of the base unit.

FIG. 4 shows a perspective view of the back side of the base unit.

FIG. 5 shows a front view of the receiver.

FIG. 6 shows a back view of the receiver.

FIG. 7 shows a front view of the base unit.

FIG. 8 shows a back view of the base unit.

FIG. 9 shows a left side view of the receiver.

FIG. 10 shows a right side view of the receiver.

FIG. 11 shows a left side view of the base unit.

FIG. 12 shows a right side view of the base unit.

FIG. 13 shows a top view of the receiver.

FIG. 14 shows a bottom view of the receiver.

(Continued)

FIG. 15 shows a top view of the base unit; and, FIG. 16 shows a bottom view of the base unit.
